UNITED STATES PATENT OFFICE.

JOHN MCTAMMANY, OF WORCESTER, MASSACHUSETTS.

MECHANICAL MUSICAL INSTRUMENT.

SPECIFICATION forming part of Letters Patent No. 390,386, dated October 2, 1888.

Application filed June 20, 1887. Serial No. 241,839. (No model.)

To all whom it may concern:

Be it known that I, JOHN MCTAMMANY, a citizen of the United States, residing at Worcester, in the county of Worcester and State of Massachusetts, have invented certain new and useful Improvements in Automatic Musical Instruments, of which the following, together with the accompanying drawings, is a specification sufficiently full, clear, and exact to enable persons skilled in the art to which this invention appertains to make and use the same.

The objects of my present invention are, first, to provide an automatic musical instrument having a sheet-propelling mechanism, the operation of which is controlled pneumatically by perforations in the sheet which is propelled thereby; second, to provide in an automatic musical instrument means for automatically propelling the music-sheet by pneumatic pressure or air-current induced by the bellows or other wind-inducing apparatus, and devices for controlling the action thereof by the perforated music sheet; third, to provide a perforated music-sheet having series of perforations for controlling the action of the sound-producing devices, and in combination therewith one or more series of perforations for controlling motor mechanism, whereby the sheet-propelling devices are operated. These objects I attain by means substantially such as explained in the following description, the particular subject-matter claimed being hereinafter definitely specified.

In the drawings, Figure 1 is a plan view of so much of an automatic musical instrument as will illustrate the nature of my invention. Fig. 2 is a vertical transverse section of the same at line X X on Fig. 1. Fig. 3 is a diagram (plan and section) illustrating the method whereby two motors may be operated by a single row of perforations with the controlling-sheet.

In carrying out my invention I employ a tracker-range similar to that heretofore employed in automatic musical instruments wherein the sounding devices are controlled by pneumatic actions, over which tracker-range the music-sheet is drawn from the spool to the winding-roll, said sheet preferably acting as a valve for the tracker-ducts. Said tracker is provided with the usual windways for the sounding-device actions, and also with addi-

tional windways which lead to pneumatics which control air-inlet valves that open and close passages leading to pneumatic motors or collapsible chambers, the movable parts of which are connected by a suitable pawl and ratchet or equivalent mechanism for operating the winding-roll, or with an auxiliary wheel or shaft, by which rotative movement is imparted to said winding-roll. The action of the air-inlet valve changes the communication from the interior of the motor or collapsible chamber either to the exterior atmosphere or to the interior of the wind-chest, so that said motor or collapsible chamber will become inflated or collapsed accordingly as the valve is shifted and the atmospheric pressure varies between that of the external air and internal pressure of the wind-chest. Two or more sets of such collapsible chambers or motors and their controlling and connecting devices are employed, so that one set may be in operation, driving the winding-roll and advancing the music or controlling sheet while the others are recovering or returning to normal position, thus giving by the joint action of the several motors a continuous forward motion to the sheet.

The music-sheet or controlling-strip I provide with series of perforations distinct from and in addition to the perforations employed for controlling the sounding devices, and which serve for alternately opening and closing the auxiliary ducts or windways formed through the tracker and leading to the pneumatics that actuate the puppets or air-inlet valve, which change the direction of air current or pressure in the collapsible chambers, so that when the movement is once started the operation of the driving mechanism is controlled and kept in motion by the perforated sheet, which is propelled or operated thereby.

In reference to parts, A denotes the main wind-chest of an automatic musical instrument having a tube-board, a, containing reeds or other sound-producing devices and valve mechanism disposed in connection therewith for operation in any suitable or well-known manner, whereby the action of sounding devices is controlled by the perforated music-sheet as it passes forward over the tracker-range.

B indicates the bellows, and B' the exhaust

ers or feeders, of any well-known construction, whereby air-pressure in the wind-chest is exhausted for inducing wind-currents or pneumatic pressure for operating the instrument.

5 A' indicates an auxiliary chamber in connection with the wind-chest and connected by a passage, c, with a supplementary chamber, C, in which is a valve or puppet, D, fitted to close either the passage c, leading into the wind chest, or an opposite passage, d, leading from the exterior air into said supplemental chamber, as indicated.

In the present instance the chamber A' has 15 a partition across it, through which are formed air-passages, for which a cut-off, slide, or shutter is provided for closing said passages, and thereby stopping of the motor action.

E indicates the operating-motor consisting, 20 preferably, of a collapsible chamber or bellows pneumatic the interior of which connects by a passage, e, with the supplemental chamber C, so that its interior air-pressure will correspond with the air-pressure in said 25 supplemental chamber C. The movable part of the pneumatic motor is connected by an arm, E', with a pawl or operating device, G, that engages a ratchet-wheel, F', connected with the winding-roll F, so that when the motor 30 collapses, the power and movement will be transmitted to and operative for rotating the winding roll. A spring, f, is in the present instance employed for pressing the pawl G against the ratchet-wheel F'. A rocker-bar, 35 H, arranged adjacent to the pawl G, is adapted to be turned backward for throwing the pawls out of engagement with the ratchet-wheels, and thus releasing the winding-roll, so that the music-sheet M can be run back or rearward 40 onto the spool or rewinding roll J.

A motor, E, pawl G, and ratchet F are arranged at each end of the winding-roll, so that one set will be exerting its force for advancing the winding-roll, while the other set is recovering or returning to normal position.

45 If in any instance it is preferred, more than two sets of motors E, pawls and ratchet-wheels, operating as described, may be employed for propelling the winding-roll, and 50 said ratchet-wheels, instead of being arranged directly upon the winding-roll axle, can be arranged upon an auxiliary shaft, said shaft in turn being connected with the winding-roll axle by suitable driving belt or gearing, as 55 may be most convenient in the disposition of the mechanism in the instrument.

The pawl and ratchet mechanism, although herein shown as engaging by means of teeth, can, if preferred, be made to act by frictional 60 or binding contact, as in any of the well-known mechanical equivalents of pawl-and-ratchet actions for transmitting power and movement from the vibrating pneumatic E to the rotating shaft or winding-roll F, which 65 carries the music-sheet.

The tracker I, over which the music-sheet passes, is provided with windways or ducts

for the sounding-device action, and also with additional ducts, i and i', one of which leads to the pneumatic K, beneath the stem D' of the 70 puppet or valve D, as shown in Fig. 2. Said pneumatic is preferably made as a circular flexible diaphragm supporting a disk with the valve-stem resting on its center without being connected thereto, and is provided with a small 75 weight, k', so that it will close quickly. In the passage leading to said pneumatic is a pin-hole escapement, as at l, for exhausting the pneumatic when the tracker-duct is closed.

In the present instance two sets of pneumatics, puppet-valves, and air-ducts, respectively arranged at each side of the instrument to correspond with the two motors E E, are employed; but I do not desire to confine my invention to this particular arrangement of 85 parts, as said devices could be arranged both at one side or in any convenient position for effecting equivalent operation.

The music or controlling sheet M is provided with a series of perforations, m, distinct from 90 and in addition to the music-perforations that control the sounding devices, and said perforations m are disposed in a manner to alternately open and close the respective ducts i i'. When the duct i is opened, (the wind-chest A 95 being exhausted,) the pneumatic K immediately becomes inflated, lifting the valve D from its seat to the top of the chamber, and thereby opening the passage c and closing the passage d into said chamber, thus putting the motor E 100 in communication with the interior of the wind-chest and exhausting the pressure from its interior, so that the excess of the atmospheric pressure on the exterior of the motor E causes it to immediately collapse, thereby moving the pawl G, which is engaged with the ratchet F, and consequently effecting a partial rotation of the winding-roll F. Then, when the air-duct of the tracker is closed by the solid portion of the sheet, the pneumatic K is 105 immediately exhausted and collapsed, allowing the puppet D to drop to the position shown in Fig. 2, closing the passage c and opening the passage d, so that the interior of the motor E will be in direct communication with the exterior atmosphere, thereby allowing the movable part of said motor to drop by gravity to its normal position and allow the pawl to recover or take a new hold upon the ratchet-wheel. If in any instance it is preferred, a 110 spring or weight may be combined with the motor to bring it more readily to normal position.

A friction device, P, is combined with the winding-roll F or the shaft on which the ratchet-wheels F' are mounted, to prevent the said wheels and winding-roll from rotation, except as forced forward by the ratchets, and an adjusting device or threaded stud, P', is combined with the friction-presser for regulating 115 the tension of the friction.

The devices for putting on and taking off the music-sheet spool J on its supporting-frame R may be such as are well known and at present

employed in automatic instruments, and need not, therefore, be herein described or shown.

The rewinding of the music-sheet from the winding-roll to the spool J can be effected by 5 a crank, J', after the bar H has been turned back to relieve pawls from the ratchet mechanism, or by other suitable means.

In Fig. 3 I have illustrated a method whereby two motors can be controlled by a single 10 row of holes, m, in the perforated controlling-strip. In this the two ducts *i* and *i'* are formed in the tracker at the same interval of its length, but at different positions in its width, and the holes *m* in the perforated strip are formed at 15 such distances apart that one of said ducts, *i*, will be closed while the other, *i'*, is opened, and vice versa, as the perforated strip is moved along over the tracker.

S indicates a slide, cut-off, or shutter arranged 20 in the upper part of the chamber A' for closing the air-passages *v* and stopping off the motor action. Said slide may be operated by a rod, S', projecting through the wall of the auxiliary chamber, connected with a stop-pull 25 or worked in other suitable manner. When the passage *v* is closed, the exhaust action cannot take effect on the motors E. By partially closing the slide S to a greater or less degree the speed of action of the motors E and parts 30 operated thereby can be increased or diminished, and the execution of the music thus regulated as desired.

What I claim as of my invention, and desire to secure by Letters Patent, is—

35 1. A music sheet for automatic musical instruments, having the rows of perforations *t* for controlling the action of sound-producing devices and two (or more) additional series of longitudinally-disposed perforations, *m*, in 40 successive order throughout the length of said sheet, one series consecutively spaced at alternating intervals with the other series, as shown and described, whereby said sheet is adapted for effecting the operation in pneumatic-motor mechanism for propelling the sheet.

45 2. In an automatic musical instrument, a pneumatic motor having connections for propelling the perforated music-sheet, in combination with a perforated sheet propelled thereby, having a series of perforations that control the sounding devices and an auxiliary series of perforations that control the supple-

mental valves, whereby the inflow and outflow of air to operate said pneumatic sheet-propelling motor is regulated, substantially as set 55 forth.

3. In an automatic musical instrument, the combination, with the sheet-propelling rolls or winding-spool, of a pneumatic motor (or motors) for imparting motion to said sheet-propelling rolls, operated by air-pressure induced by the bellows or other wind-inducing apparatus of the instrument, having suitable windways and ducts for governing the pneumatic action, and a baud or sheet carried by 60 said propelling mechanism, having a series of perforations for inducing the consecutive collapse and inflation of said propelling or motor pneumatics, substantially as set forth, whereby the propelling action of the mechanism is regulated by or dependent upon the sheet thereby 70 propelled.

4. In an automatic musical instrument, the combination, substantially as described, of the winding-roll having ratchet-wheels connected therewith; the pneumatic motors provided with pawls that engage said ratchets for operating said roll, pneumatically-operated valves D, controlling the air-passages of said motors, and a perforated music sheet having an auxiliary series of perforations that regulate the opening and closing of said valves, for the purpose set forth.

5. In an automatic musical instrument, the combination of the winding-roll and rewinding-roll carrying the perforated sheet, the collapsible pneumatic motors having connections for imparting rotative action to said winding-roll, and air-passages to the external air and into the interior of the wind-chest, a primary 85 valve, D, that alternately opens and closes said air-passages, a pneumatic for working said primary valve, provided with a windway leading to a tracker-duct, and a perforated music-sheet provided with auxiliary series of perforations that control said ducts, substantially 90 as and for the purpose set forth.

Witness my hand this 31st day of May, A. D. 1887.

JOHN McTAMMANY.
